ELEVATOR SYSTEMS

William F. Eames, Westfield, N.J., assignor to Westinghouse Electric Corporation, East Pittsburgh, Pa., a corporation of Pennsylvania

Application October 10, 1958, Serial No. 766,565

8 Claims. (Cl. 187—29)

This invention relates to elevator systems and it has particular relation to an elevator system which basically provides unidirectional selective collective elevator service.

Various aspects of the invention are applicable either to an elevator system having a single elevator car or to a system having multiple elevator cars arranged in a bank. Furthermore, aspects of the invention are applicable to elevator systems wherein attendants are provided in the elevator cars for the purpose of operating the elevator cars or to automatic systems wherein the elevator cars may operate without car attendants. Since the invention is particularly suitable for automatic elevators, it will be described with particular reference to an automatic elevator system having a bank of elevator cars.

Elevator systems may be designed to provide one or more types of passenger service, one of which is unidirectional selective collective service. For unidirectional selective collective operation the elevator system may be so designed that an elevator car does not accept calls for prospective passengers located at the various floors of the building served by the elevator system during one direction of travel of the elevator car. Thus, if the elevator car is loaded at the lower terminal floor, it proceeds upwardly but fails to stop in response to any call for up service registered by a prospective passenger at any of the intermediate floors of the building. If desired, the elevator car may stop in response to car calls which are registered by passengers within the elevator car. During the return trip of the elevator car, stops are made in response not only to calls registered by passengers within the elevator cars, but to calls registered by prospective passengers at the floors approached by the elevator car. Such operation is known as down collective service.

In this type of installation only one corridor push button is required for each floor station which is provided at each floor of the building so that prospective passengers may register calls for elevator service from each floor. For some of the floors, calls will be registered not only by passengers within the elevator car but by prospective passengers located at such floors. Consequently, one stop at each of these floors serves both classes of passengers and materially increases the efficiency of the elevator system. Such a system results not only in an improvement in efficiency but it permits a substantial simplification of circuits and a reduction in the number of circuit components required, as is pointed out in the Eames Patent No. 2,709,503, which issued May 31, 1955, and which is assigned to the same assignee as the subject application.

The down collective system, on the other hand, is open to the criticism that when a passenger from the lower half of the building, for example, wishes to travel to the upper half of the building, he must enter a down-moving car and thereafter travel to the first floor. Then he must wait for the car to start again to move in an upward direction. He may also have to wait for one or more stops in response to registered car calls as he travels back toward

2

the floor he left. Thereafter, the car will stop at the floor desired by the passenger. From the passenger's point of view, there is a great deal of needless loss of time before useful car movement starts, that is, movement of the car from the floor at which he enters the car to the floor above at which he wishes to depart the car. Such loss of time has occurred, of course, because the passenger cannot stop an up-moving car at his floor.

In accordance with the invention, a basically unidirectional selective collective elevator system is provided with a bidirectional selective collective feature, overcoming the above-mentioned drawbacks of the former system while at the same time retaining its advantages. The improvement is accomplished in a down collective system, for example, by providing means whereby a passenger disposed at a floor intermediate the upper and lower terminal floors who wishes to travel to a floor above may register a call to stop the next up-moving car, although only a single floor-call push button is provided for each floor station.

In a preferred embodiment of the invention, means are furnished which are responsive to special actuation of the single floor-call push button provided for each of the intermediate floors to register up floor calls for elevator service. Preferably, such means take the form of circuits which are responsive to the pressing and holding of a corridor-call push button by a prospective passenger as an up-moving elevator car approaches the floor associated with that push button. The circuits operate to stop the up-moving car at the desired floor. Subsequently, the passenger may enter the elevator car to register a call for a floor above, after which the elevator car moves upwardly to answer such call. In order to register a down call for elevator service from an intermediate floor, a prospective passenger, instead of pressing and holding the single floor-call push button disposed at his landing, is required merely to press and release the push button. Thereafter, the next down-moving car will stop to answer the call.

It is, therefore, an object of the invention to provide an improved elevator system basically having unidirectional selective collective operation.

It is an additional object of the invention to provide a basically unidirectional selective collective elevator system with a bidirectional selective collective feature.

It is a further object of the invention to provide a basically down collective elevator system with an up collective feature.

It is still another object of the invention to provide an elevator system with a selective collective control system in which either up or down collective operation may be had at will, as determined by the mode of operation of a single corridor push button disposed at each of the floors served by the elevator system.

It is another object of the invention to provide a down collective elevator system in which an elevator car may be stopped on its up trip in response to a floor call by special actuation of the single floor-call push button furnished for each of the floors.

Other objects of the invention will be apparent from the following description taken in conjunction with the accompanying drawing, in which:

Fig. 1 is a schematic view with the electrical circuits shown in straight line form of a portion of an elevator system embodying the invention;

Figs. 2 and 3 are schematic views with electrical circuits shown in straight line form of additional portions of the elevator system illustrated in Fig. 1;

Figs. 1A, 2A and 3A are key representations of electromagnetic switches and relays employed in the circuits of Figs. 1, 2 and 3. If Figs. 1A, 2A and 3A are placed in horizontal alignment with Figs. 1, 2 and 3, respectively, it will be found that the associated coils and contacts

of the relays and switches of the horizontally aligned drawings are substantially in horizontal alignment.

Because of the complexity of the system, a number of conventions has been adopted. Although the invention may be incorporated in an elevator system having various numbers of elevator cars designed to service various floors or landings of a building, the invention will be described with reference to an elevator system employing two cars for the purpose of serving a building having six floors or landings. The elevator cars will be designated by the reference characters A and B.

Inasmuch as similar circuits are provided for each of the elevator cars, a component for the elevator car B will be identified by the reference character employed for the corresponding component associated with the car A, but preceded by the letter B to indicate that the component under consideration is associated with the elevator car B. It will be understood that the elevator car B and all components specific thereto may be omitted if a single-car system is desired.

Relays and switches are employed which may have a number of sets of contacts which are substantially simultaneously operated. Each set of contacts is identified by the reference character employed for the relay having the contacts followed by a numeral indicating the specific set of contacts. Thus, the reference characters U1 and U3 represent the first and third sets of contacts of the up switch U for the elevator car A.

An electromagnetic switch or relay may have make or front contacts. Such contacts are closed when the switch or relay is energized and picked up. The contacts are open when the switch or relay is deenergized and dropped out. In addition, relays and switches may have break or back contacts. Such contacts are closed when a relay or switch is deenergized and dropped out. The contacts are opened when a relay or switch is energized and picked up.

To facilitate the presentation of the invention, the following apparatus is listed:

Apparatus for car A:

V—Speed relay
U—Up switch
M—Running relay
D—Down switch
G—Holding relay
E—Inductor slowdown relay
F—Inductor stopping relay
W—Up preference relay
X—Down preference relay
70T—Non-interference relay
J—Reversing relay
DR—Door relay
T—Car-call stopping relay
1CR to 6CR—Car-call registering relays
78—No-call relay
78U—Call-above relay

Apparatus common to all cars:

1DR to 6DR—Floor-call relays
1D to 6D—Down floor-call registering relays
UST—Up stop relay
DST—Down stop relay

Fig. 1 shows motor control circuits for the elevator cars A and B. For the elevator car A, the control circuits illustrated in Fig. 1 include a speed relay V, an up switch U, a car-running relay M, a down switch D, a holding relay G, a slowdown inductor relay E, an inductor stopping relay F, an up preference relay W, a down preference relay X, a non-interference relay 70T and a door relay DR. The control circuits are energized from a direct-current source of electrical energy represented by two buses L1 and L2. (The buses BL1 and BL2 may be energized from the same source and may be tied to the buses L1 and L2, respectively, by conductors LT1 and LT2.)

The elevator car A is connected to a counterweight 16 by means of one or more ropes 11 which pass over a sheave 12. The sheave 12 is secured to a shaft 13 which is rotated by means of suitable motive means. Although any suitable motive means may be employed, it will be assumed that a variable voltage control is employed to control the energization of a direct-current motor 14 which has its armature 14A secured to the shaft 13. The motor 14 has a field winding 14F which is permanently connected across the buses L1 and L2.

By inspection of Fig. 1, it will be noted that the armature 14A and an armature 15A of a direct-current generator 15, together with a series field winding 15S for the generator, are connected in a loop series circuit. The generator also has a field winding 15F which is separately excited for the purpose of controlling the direction and magnitude of the energization of the motor armature 14A.

Because of the large number of circuits employed in an elevator system, it is common practice to provide an elevator system with a floor selector 16. Such a floor selector may include an insulating panel 16P, on which a plurality of rows of contact segments is mounted. The floor selector includes a brush carriage 16C which is moved relative to the contact segments in accordance with motions of the elevator car. Thus, the movement of the brush carriage relative to the contact segments corresponds on a reduced scale to the movement of the elevator car relative to the floors of the building served by such car. The movement of the brush carriage may be effected by a screw 16S which is mounted for rotation on the panel 16P and which is in threaded engagement with the carriage. This screw is coupled through suitable gearing 16G to the shaft 13 for rotation by the shaft.

The brush carriage has a separate brush provided for each of the rows of contact segments. Although only two rows of contact segments are illustrated in Fig. 1, it will be understood that as many rows are provided as are required for the elevator system. For example, as the elevator car proceeds from the lower terminal floor upwardly, a brush bb on the brush carriage successively engages the contact segments b2 to b6. The numerals in the reference characters b2 to b6 represent the floors with which the contact segments are associated. Thus, as the elevator car approaches the second floor, the brush bb engages the contact segment b2 to prepare circuits which are completed if the elevator car is to stop at the second floor in response to a call registered by a passenger within the elevator car.

As a further example, the brush cc on the brush carriage successively engages the contact segments c2 to c6 which are associated respectively with the second to sixth floors. Thus, as the elevator car stops at the second floor in response to a car call, the brush cc engages the contact c2 to complete a cancelling or resetting circuit for the purpose of resetting the car call registered for the second floor.

The shaft 13 also carries a brake drum 17. This brake drum cooperates with a spring-applied electromagnetically-released brake of conventional construction. Thus, in Fig. 1, a brake shoe 17S is biased against the drum 17 in braking position by means of a spring (not shown). The shoe has secured thereto a magnetic armature 17M which is associated with a releasing coil or brake coil 17B. When the brake coil 17B is energized by closure of either of the sets of make contacts U1 or D1, the brake shoe 17S is retracted against the bias of the spring to release the brake drum 17 and permit rotation of the shaft 13.

Returning to the generator field winding 15F, it will be noted that this field winding is connected across the buses L1 and L2 through a reversing circuit. For example, when the make contacts U2 and U3 are closed, the field winding 15F is connected across the buses with proper polarity for up travel of the elevator car. When

the make contacts D2 and D3 are closed, the field winding 15F is connected across the buses with proper polarity for down travel of the elevator car. The energization of the field winding 15F may be effected through the resistor R1 when the resistor is not shunted by the make contacts V1 of the speed relay.

The elevator car A contains a plurality of push buttons 1c to 6c for the purpose of registering calls by passengers in the elevator car respectively for the first to sixth floors of the building served by the elevator car. In addition, the elevator car has mounted thereon two inductor relays E and F. These inductor relays may be of conventional construction and are employed respectively for controlling the slowdown and stopping of the elevator car. The inductor slowdown relay E is employed for operating break contacts E1 and E2. This relay has a normally incomplete magnetic circuit. Consequently, energization of the coil of the relay alone is insufficient to operate the contacts. If the elevator car during down travel approaches a floor at which it is to stop, the coil of the slowdown relay E is energized, and as the car continues its approach, the inductor relay reaches an inductor plate DEP for such floor. The inductor plate completes a magnetic circuit for the relay, which results in opening of the break contacts E2. It will be understood that a similar inductor plate is provided for each of the floors at which the elevator car A is to stop during down travel. The opening of the contacts E2 initiates a slowdown operation of the elevator car.

If the elevator car A is to stop at a floor during up travel, the coil of the relay E is again energized, and when the relay reaches the inductor plate UEP associated with the floor, a magnetic circuit is completed for the relay which results in opening of the break contacts E1. The opening of such contacts initiates a slowdown operation of the elevator car. A similar inductor plate is provided for each of the floors at which the elevator car is to stop during up travel thereof. It will be understood that the inductor plates are mounted in the hoistway at positions selected to provide suitable slowdown distances for the elevator car.

The inductor stopping relay F cooperates in a similar manner with inductor plates DFP and UFP. One of the inductor plates DFP is provided for each of the floors at which the elevator car is to stop for down travel thereof. One of the inductor plates UFP is provided for each of the floors at which the elevator car A is to stop during up travel thereof. Operation of the break contacts F1 and F2 of the stopping relay F initiates a stopping operation of the elevator car. It will be understood that the inductor plates DFP and UFP are positioned in the hoistway at suitable points to stop the elevator car accurately at each of the associated floors.

The speed relay V is connected across the buses L1 and L2 through either of two parallel arms. One of these arms includes make contacts U4 of the up switch U, a limit switch 19 and the break contacts E1 of the inductor slowdown relay E. The limit switch 19 is of conventional construction. It is normally closed and is opened as the elevator car nears its upper limit of travel.

The second arm for the speed relay V includes in series the make contacts D4 of the down switch D, a limit switch 20 and the break contacts E2 of the inductor slowdown relay E. The limit switch 20 is a normally closed cam-operated switch which is opened as the elevator car nears its lower limit of travel.

For the running relay M to be energized, the make contacts DR1 of the door relay DR must be closed to indicate that all of the doors associated with the elevator car A are closed. Initial energization of the running relay M also requires closure of the break contacts 70T1 of the non-interference relay 70T to indicate that the elevator car has remained at its last stop for a period sufficient to permit discharge or entry of passengers, and closure of the break contacts 78-1 of the no-call relay

to indicate that a call for elevator service has been registered which the elevator car A can answer.

The energization of the running relay M initially is completed through either of two parallel paths. One of these paths include in series make contacts W1 of the up preference relay W, break contacts F1 of the inductor stopping relay F, normally closed contacts of a limit switch 21, and the coil of the up switch U. The limit switch is a cam-operated switch which is opened as the elevator car A nears its upper limit of travel. When the running relay M is energized through the first path, make contacts U5 close to complete a holding circuit around the contacts 70T1, 78-1 and W1.

The second path for initially completing the energization of the running relay M includes in series the make contacts X1 of the down preference relay X, the break contacts F2 of the inductor stopping relay F, normally closed contacts of a cam-operated limit switch 22 and the coil of the down switch D. The limit switch 22 is opened as the elevator car nears its lower limit of travel. When the running relay M is energized through the second path, make contacts D5 close to complete a holding circuit around the contacts 70T1, 78-1 and X1.

Energization of the holding relay G and of the inductor relays E and F requires closure of the make contacts M1 which occurs when the car is running. In addition, initial energization of these relays requires closure of one of four sets of contacts. Closure of make contacts T1 occurs when the elevator car is to stop at the next floor in response to a registered car call. Closure of make contacts UST1 indicates that the elevator car during up travel is to stop at the next floor reached by the elevator car in response to an up floor call which is registered by a prospective passenger for such floor. Closure of the make contacts DST1 indicates that the elevator car during down travel is to stop at the next floor reached by the elevator car in response to a down floor call which is registered by a prospective passenger for such floor. Finally, closure of make contacts J1 indicates that the elevator car during up travel is to stop and reverse at the next floor which is the farthest floor for which a car call or a down floor call is registered. When the holding relay G is energized, it closes its make contacts G1 to establish a holding circuit around the contacts T1, UST1, DST1 and J1.

For the up preference relay W to be energized, break contacts D6 and X2 must be closed. In addition, the contacts of a normally closed limit switch 24 must be closed. The limit switch 24 is cam operated to open as the elevator car nears the upper terminal floor. It should be noted that the up preference relay W during an up trip of the elevator car remains energized as long as the limit switch 24 and the break contacts J2 of the reversing relay J are closed. If the contacts J2 open during such trip before the limit switch opens, the up preference relay W remains energized as long as the make contacts M2 remain closed.

For the down preference relay X to be energized the break contacts U6 and W2 must be closed and a mechanical limit switch 25 must be closed. The limit switch 25 is normally closed and is cam operated to open as the elevator car A nears its lower terminal floor.

It will be observed that for either the up or the down preference relay to be energized, at least one of two parallel sets of contacts, make contacts M7 of the running relay M and break contacts 78-3 of the no-call relay 78, must be closed. As long as the elevator car is running, the running relay M is picked up and the make contacts M7 are closed. The break contacts 78-3 are closed as long as there is a call for service which may be answered by the elevator car A. If the elevator car A is stopped at a floor (contacts M7 are open) and if no call is registered which may be answered by the elevator car A (contacts 78-3 are open), the relays X and Y both

will be dropped out. Desirably, the down preference relay X has a slight time delay in pickup, i.e. the up preference relay W has a priority in pickup over the down preference relay X.

The non-interference relay 70T is energized through the make contacts M3 as long as the elevator car is running. When the contacts M3 open during the stopping of the elevator car at a floor, the relay 70T remains picked up for a predetermined time sufficient to permit entry or discharge of passengers relative to the elevator car. The dropout time of the relay may be determined in any suitable way and is represented by a resistor R2 which is connected across the relay coil.

The door relay DR is a conventional relay which is connected across the buses for energization through door contacts. Each of the hoistway doors for the elevator car A and the car doors have contacts connected in series with the door relay DR to permit energization of the door relay only when all of the doors are closed and in safe condition.

For the reversing relay J to be energized, the break contacts X3 must be closed to indicate that the elevator car is not conditioned for down travel; the break contacts 78-2 of the no-call relay 78 must be closed to indicate that a call is registered which can be answered by the elevator car A; and the break contacts UST2 of the up stop relay UST must be closed to indicate that an up floor call is not being answered by the elevator car A. The initial energization of the relay J is effected through make contacts 78U1 of the call-above relay 78U as the elevator car A approaches the farthest floor in the up direction for which a call is registered. When energized, the relay J closes its holding contact J3 for the purpose of establishing a holding circuit around the contacts 78U1.

Floor stations are provided at the floors of the building at which prospective passengers may register calls for elevator service. Thus, for the second floor a push button 2F may be operated to register a floor call. A similar push button is provided for each floor from which a floor call may be registered. These push buttons are common to all cars.

Also located at each floor is a car position indicator for each of the elevator cars of the system. Thus, for the second floor, car position indicators PI and BPI for the elevator cars A and B, respectively, are provided. Similar car position indicators are located at each of the other floors for which elevator service may be provided. These car position indicators continuously indicate the positions of their respective associated elevator cars with respect to the floors of the building. Since such car position indicators are well known in the art, it appears unnecessary to describe them further.

Figure 2

Fig. 2 illustrates the floor call registering circuits for the elevator system. As heretofore mentioned, the push buttons 1F through 6F, shown in the upper part of Fig. 2, are located respectively at the first to sixth floors and may be operated by prospective passengers desirous of transportation to other floors. It will be understood that each of the push buttons is biased towards contact open position. These push buttons are associated respectively with floor-call relays 1DR through 6DR. These floor call relay circuits cooperate with a row e2 through e6 of contact segments located on the floor selector 16 of Fig. 1. Associated with the contact segments e2 through e6 is a brush ee in series with which are make contacts W3 of the up preference relay W and the up stop relay UST, which has a time delay in dropout. This time delay may be determined in any suitable way and is represented by a resistor R3 which is connected across the relay coil.

The lower part of Fig. 2 illustrates circuits for the down floor-call registering relays 1D through 6D and

their associated canceling coils 1DN through 6DN, respectively. These registering circuits cooperate with the two rows f1 through f5 and g1 through g6 of contact segments located on the floor selector 16. Associated with these contact segments are brushes ff and gg, respectively. In series with the brush ff are make contacts X4 of the down preference relay X; in series with the brush gg are break contacts M4 of the running relay M.

The association of the various components of Fig. 2 may be understood best by consideration of certain representative operations. If a prospective passenger located at the second floor desires transportation in the down direction, he presses the push button 2F to energize through the normally open switch of the push button, the floor-call relay 2DR for the second floor. This relay closes its make contacts 2DR1 to energize the down floor-call registering relay 2D. Opening of the break contacts 2DR2 has no immediate effect on operation of the system. The relay 2D closes its make contacts 2D1 to establish a holding circuit around the contacts 2DR1. Thus, when the push button 2F is released, the relay 2DR drops out to open its contacts 2DR1; but the relay 2D remains picked up. By inspection, it will be noted that the contacts 2D1 now connect, through the now closed contacts 2DR2, the segment f2 for the elevator car A and a similar segment Bf2 for the elevator car B to the bus L1.

As the elevator car A while traveling in the down direction nears the second floor, the brush ff of the floor selector engages the contact segment f2 to complete the following circuit:

L1, 2D1, 2DR2, f2, ff, X4, DST, L2

(Note that since the elevator car is traveling in the down direction the make contacts X4 are closed.) The energized down stop relay DST initiates a stopping operation of the elevator car at the second floor.

Upon continued motion of the elevator car A toward the second floor, the brush gg engages the contact segment g2. As the elevator car stops at the second floor, the heretofore open contacts M4 close to complete the following circuit:

L1, 2D1, 2DN, g2, gg, M4, L2

The coil 2DN is a canceling coil which is wound on the same core as the coil 2D but which is energized in opposition thereto. Consequently, the energization of the canceling coil 2DN results in neutralizing of the coil 2D and resetting of the registering relay. As the elevator car comes to a stop, the brush ff preferably passes slightly beyond the contact segment f2. However, the brush gg preferably remains in engagement with the contact segment g2 as long as the elevator car A remains at the second floor.

It should be noted that had the elevator car B answered the call at the second floor the brush Bff would have engaged the contact segment Bf2 to stop the car B. Furthermore, as the elevator car B neared the second floor, the brush Bgg would have reached the contact segment Bg2 to reset the registering relay 2D.

Assume that instead of approaching the second floor while traveling in the down direction the elevator car A approaches the second floor while traveling in the up direction after the down floor call is registered by the prospective passenger at the second floor by pressing and releasing the push button 2F, as above described. It will be observed that since the down preference relay X (Fig. 1) is deenergized while the car A is traveling in the up direction, the make contacts X4 are open. Consequently, the down stop relay DST is unable to pick up to initiate a stopping operation of the car as the car approaches the second floor during upward movement. The car, therefore, continues to move upwardly, by-passing the second floor.

Assume next that the prospective passenger at the second floor desires transportation from the second floor in the up direction. Instead of pressing and releasing the push button 2F, the passenger presses and holds the button to maintain the normally open switch thereof in closed condition. As the elevator car A approaches the second floor during up travel, the brush ee engages the contact segment e2 to complete the following circuit:

L1, 2F, e2, ee, W3, UST, L2

(Note that since the car is traveling in the up direction the make contacts W3 are closed.) The energized up stop relay UST initiates a stopping operation of the elevator car A at the second floor.

Upon continued motion of the elevator car A toward the second floor, the brush gg engages the contact segment g2 to energize the canceling coil 2DN, which thereby resets the registering relay 2D after the break contacts M4 close in the manner described above. Observe that had the elevator car B, while traveling in the up direction, answered the up floor call at the second floor, the brush Bee would have engaged the contact segment Be2 to stop the elevator car B. In addition, as the car B neared the second floor, the brush Bgg would have reached the contact segment Bg2 to reset the registering relay 2D.

Circuits similar to those discussed for the second floor are associated with each of the push buttons 2F through 5F for the intermediate floors of the building and may be readily traced in Fig. 2. Inasmuch as the elevator car cannot stop at the upper terminal floor during down travel, a contact segment in the f row is not required for the sixth floor. Since the elevator car A during up travel must not move beyond the upper terminal floor, a single contact segment e6 is connected permanently to the bus L1. Consequently, as the elevator car A approaches the sixth floor the brush ee engages the contact segment e6 to stop the elevator car A at the sixth floor.

The floor-call registering circuits for the first or lower terminal floor may be similar to those discussed for the second floor. However, inasmuch as the elevator car A must not move beyond the first floor during down travel thereof, a single contact segment f1 is connected permanently to the bus L1. Consequently, as the elevator car A approaches the first floor, the brush ff engages the contact segment f1 to stop the elevator car A at the first floor. Since the elevator car A cannot stop at the lower terminal floor during up travel, a contact segment in the e row is not required for the first floor.

Figure 3

The upper part of Fig. 3 illustrates circuits for registering calls for floors desired by passengers within the elevator car. Registration of a call for such a passenger is effected by operation of one of the car-call push buttons 1c to 6c. For example, when the push button 2c is operated, the car-call registering relay 2CR is connected across the buses L1 and L2. This relay closes its make contacts 2CR1 to establish a holding circuit around the push button 2c. It will be understood that each of the push buttons is biased towards contact open position. Each of the push buttons is similarly associated with one of the car-call registering relays 1CR to 6CR, respectively.

The car-call registering circuits have associated therewith four rows of contact segments which are located on the floor selector 16 (Fig. 1). The rows of contact segments b2 to b6 and c2 to c6 previously were mentioned. In addition, each contact of a row of contact segments a1 to a5 is successively engaged by a brush aa during travel of the elevator car and cooperates with circuits for initiating stops of the elevator car during up travel. Each contact of a row of contact segments d1 to d5 coacts with a brush dd for the purpose of canceling registered car calls which are answered during up travel of the elevator car.

It is believed that the car-call stopping circuits can be understood best by a presentation of representative operations. If the elevator car A is to stop at the second floor during up travel thereof in response to a registered car call, the relay 2CR is energized and the contacts 2CR1 are closed. As the car approaches the second floor, the brush bb engages the contact segment b2 to complete the following circuit:

L1, 2CR1, b2, bb, W4, T, M5, L2

10 (Note that since the car is traveling in the up direction the make contacts W4 are closed.) The energization of the car-call stopping relay T results in stopping of the elevator car A at the second floor.

15 As the elevator car nears the second floor, the brush dd engages the contact segment d2 to complete the following circuit:

L1, 2CR1, 2CRN, d2, dd, W5, M6, L2

20 The coil 2CRN is a canceling coil which is wound on the same core as the coil 2CR but which is energized in opposition thereto. Consequently, the energization of the canceling coil 2CRN results in neutralizing of the coil 2CR and resetting of the registering relay. As the elevator car comes to a stop, the brush bb preferably passes slightly beyond the contact segments b2.

25 Let it be assumed next that the car call for the second floor is registered during down travel of the elevator car. As the elevator car nears the second floor, the brush aa engages the contact segment a2 to complete the following circuit:

L1, 2CR1, a2, aa, X5, T, M5, L2

30 The energization of the car-call stopping relay T results in stopping of the elevator car A at the second floor. As the elevator car A continues to approach the second floor, the brush cc engages the contact segment c2 to complete the following circuit:

L1, 2CR1, 2CRN, c2, cc, X6, M6, L2

35 40 The energization of the canceling coil 2CRN cancels the call at the second floor. As the elevator car comes to a stop, the brush aa preferably passes slightly beyond the contact segment a2.

45 The car-call registering circuits for the second to the fifth floors are all similar and will be understood from the discussion of the circuits associated with the second floor. Because of this similarity, such car-call registering circuits are illustrated in Fig. 3 only for the second and fifth floors.

50 The car-call registering circuits for the sixth or upper terminal floor may be similar to those for the second floor. However, since the elevator car cannot stop at the upper terminal floor during down travel thereof, it follows that contact segments in the a and d rows are not required for the upper terminal floor and are not shown for such floor in Fig. 3.

55 The car-call registering circuits for the first or lower terminal floor may be similar to those discussed for the second floor. However, the elevator car cannot stop at the lower terminal floor during up travel thereof. For this reason, contact segments in the b and c rows are not required for the lower terminal floor and are not illustrated for such floor in Fig. 3.

60 65 The lower part of Fig. 3 illustrates call-above circuits for the elevator cars. Thus, the elevator car A has a call-above circuit 36 which includes in series break contacts of all of the call registering relays for floors above the second floor. The call-above circuit is associated with contact segments m2 through m6 which are located in a row in the floor selector. The call-above circuit controls the energization of the call-above relay 78U, which is connected through make contacts W6 of the up preference relay W between a brush mm, which cooperates with the contact segments, and the bus L2.

70 75 By inspection of Fig. 3, it will be noted that the break

11

contacts of the registering relays are connected between the bus L1 and the contact segment *m*2 as follows:

L1, 6CR2, 6D2, 5CR2, 5D2, 4CR2, 4D2, 3CR2, 3D2, *m*2

Each of the contact segments *m*2 through *m*5 is connected to the call-above circuit at a point such that contacts for the registering relays requiring travel of the elevator car A above the floor represented by any contact segment are all located above such contact segment. Thus, the contact segment *m*5 is connected to the call-above circuit between the break contacts 6D2 and 5CR2. The contact segment *m*4 is connected to the call-above circuit between the break contacts 5D2 and 4CR2. The contact segment *m*3 is permanently connected to the bus L1. The remaining connections are clear from Fig. 3. The brush *mm* engages and leaves each of the contact segments during up car travel in advance of the associated floor.

By inspection of Fig. 3, it will be observed that as long as a call is registered requiring travel of the elevator car to a floor above the position of the elevator car A, the call-above relay 78U cannot be energized through the call-above circuit.

A circuit connects the no-call relay 78 between the contact segment *m*2 and the bus L2 through the series-connected break contacts 2CR2, 2D2, 1CR2 and 1D2. If no call which may be served by the elevator car A is registered, the relay 78 is energized and picked up. As long as such a call is registered, however, the relay is deenergized and dropped out.

Operation—Figs. 1, 2 and 3

In order to facilitate an understanding of the elevator system, some typical operations of the system will be considered. It will be assumed first that the elevator car A is located at the first floor. It will be assumed further that down floor calls are registered at the second and fifth floors by the pressing and releasing of the push buttons 2F and 5F, respectively (Fig. 2). As a result of their energization in the manner heretofore described, the floor call relays 2DR and 5DR close their make contacts 2DR1 and 5DR1, respectively, to pick up the down floor-call registering relays 2D and 5D. The opening and closing of the break contacts 2DR2 and 5DR2 upon the pressing and releasing, respectively, of the push buttons 2F and 5F have no immediate effect on operation of the system. Closure of the make contacts 2D1 and 5D1 establishes self-holding circuits for the relays 2D and 5D, respectively. Opening of the break contacts 2D2 and 5D2 (Fig. 3) in the call-above circuit 36 results in deenergization of the no-call relay 78. Inasmuch as the elevator car A is at the first floor, the brush *mm* is not in engagement with a contact segment, and the call-above relay 78U is, therefore, dropped out.

The down floor-call registering relays 2D and 5D also open their break contacts 2D3 and 5D3, respectively, in the call-above circuit B36 for the elevator car B. The present discussion, however, will be confined to the operation of the elevator car A.

Referring to Fig. 1, it will be noted that the deenergized call-above relay 78U maintains its contacts 78U1 open to prevent energization therethrough of the reversing relay J. The no-call relay 78 closes its break contacts 78-2 to permit energization therethrough of the car-running relay M and the up switch U. Contacts 78-3 close to permit energization therethrough of the reversing relay. Closure of the break contacts 78-3 establishes the following energizing circuit for the up preference relay W;

L1, J2, D6, X2, W, 24, 78-3, L2

(Note that the down preference relay X cannot pick up, since the limit switch 25 is open, inasmuch as the elevator car A is positioned at the first floor.) The car A now is conditioned for up travel.

It will be assumed that the elevator car A has remained at the lower terminal floor for a time sufficient to permit

12

the non-interference relay 70T to time out and close its break contacts 70T1. It will be assumed further that the doors associated with the elevator car A are all closed and that the door relay DR is energized to close its make contacts DR1. The doors may be of any conventional type. For example, they may be manually opened and spring closed or they may be power operated in both directions, if desired.

Since the contacts 70T1, 78-1, W1 and DR1 are closed, 10 the following circuit is established:

L1, 70T1, 78-1, W1, F1, 21, U, M, DR1, L2

The energized up switch U closes its make contacts U1 to energize the brake coil 17B for the purpose of releasing the elevator brake. Contacts U2 and U3 close to connect the generator field winding 15F for energization with proper polarity for up travel of the elevator car. Contacts U4 close to complete an energizing circuit for the speed relay V. This relay closes its make contacts V1 to shunt the resistor R1. The elevator car now accelerates in the up direction.

Closure of the make contacts U5 establishes a holding circuit for the relays U and M around the contacts 70T1, 78-1 and W-1. Opening of the break contacts U6 has 25 no immediate effect on the system operation.

The energization of the running relay M results in closure of the contacts M1 to prepare the relays G, E and F for subsequent operation. Closure of the make contacts M2, M7 and M5 (Fig. 3) and opening of the break contacts M4 (Fig. 2) and M6 (Fig. 3) have no immediate effect on the operation of the system.

Closure of the make contacts M3 (Fig. 1) energizes the non-interference relay 70T, which opens its contacts 70T1. Because of the holding circuit established through 35 the contacts U5, opening of the contacts 70T1 has no immediate effect on the operation of the system.

Since the floor-call push button 2F has been released, the up stop relay UST (Fig. 2) cannot be energized as the elevator car proceeds upwardly and the brush *ee* engages the contact segment *e*2. Consequently, the elevator car A continues to move toward the fifth floor.

As the car A approaches the fifth floor, the brush *mm* (Fig. 3) engages the contact segment *m*5 to complete the following circuit:

45 L1, 6CR2, 6D2, *m*5, *mm*, W6, 78U, L2

The energized call-above relay 78U closes its make contacts 78U1 (Fig. 1) to complete an energizing circuit for the reversing relay J. This relay, in turn, closes its make contacts J1 to complete an energizing circuit for the relays G, E and F. Opening the break contacts J2 prepares the up preference relay W for subsequent deenergization. Closure of the make contacts J3 establishes a self-holding circuit for the relay J around the contacts 78U1. Energization of the holding relay G results in closure of the make contacts G1 to establish a holding circuit around the contacts J1.

In response to continued movement of the elevator car A toward the fifth floor, the inductor slowdown relay E is horizontally aligned with the slowdown inductor plate UEP for the fifth floor to complete a magnetic circuit which results in opening of the break contacts E1. Such opening deenergizes the speed relay V, which opens its make contacts V1 to insert the resistor R1 in series with the generator field winding 15F. As a result of the decreased energization of the field winding, the elevator car A slows to a landing speed.

Continued movement of the elevator car A toward the fifth floor brings the inductor stopping relay F into horizontal alignment with inductor stopping plate UFP for the fifth floor. The resulting completion of the magnetic circuit for the relay results in opening of the break contacts F1 to deenergize the up switch U and the running relay M.

70 The up switch U now opens its make contacts U1 to

deenergize the brake coil 17B. The brake shoe 17S now is biased against the drum 17. In addition, the make contacts U2 and U3 open to deenergize the generator field winding 15F, and the elevator car A stops accurately at the fifth floor. Opening of the make contacts U4 and U5 and closure of the break contacts U6 have no immediate effect on the operation of the system.

The running relay M when deenergized opens its make contacts M1 to deenergize the relays E, G and F. As the car stops, the inductor relays may pass beyond their operating inductor plates. The holding relay G opens its self-holding contacts G1. Opening of the make contacts M5 (Fig. 3) and closure of the break contacts M6 have no immediate effect on the operation of the system.

As is noted above, the energization of the reversing relay J resulted in opening of the break contacts J2. As the elevator car A stops, the contacts M2 of the running relay M also open to deenergize the up preference relay W. The deenergized relay W opens its make contacts W1, W3, W4, W5 and W6 and closes its break contacts W2. Closure of the break contacts W2 completes an energizing circuit for the down preference relay X, and this relay closes its make contacts X1, X4, X5 and X6 and opens its break contacts X2 and X3. Consequently, the elevator car A now is conditioned for down travel. It should be noted that the elevator car has stopped during up travel at a floor in response to a registered down floor call which is the farthest down floor call in the up direction.

Closure of the make contacts X1 prepares the down switch D for subsequent energization. Opening of the break contacts X2 and X3 prevents subsequent energization therethrough of the relays W and J, respectively. Closure of the make contacts X4 (Fig. 2) prepares the down stop relay DST for subsequent energization. Closure of the make contacts X5 and X6 (Fig. 3) has no immediate effect on operation.

The make contacts M3 in opening deenergize the non-interference relay 70T and this relay starts to time out. Until the relay times out, the contacts 70T1 remain open to prevent further starting of the elevator car.

During the stopping of the elevator car A at the fifth floor, the brush gg (Fig. 2) engaged the contact segment g5. Inasmuch as the break contacts M4 were then closed, the following canceling circuit was completed:

L1, 5D1, 5DN, g5, gg, M4, L2

As a result of the energization of the canceling coil 5DN, the registering relay 5D is reset and opens its holding contacts 5D1. Closure of the break contacts 5D2 (Fig. 3) in the call-above circuit 36 has no immediate effect on the operation of the elevator car A. Closure of the break contacts 5D3 in the call-above circuit B36 of elevator car B is assumed to have no immediate effect on the operation of the system.

The no-call relay 78 remains deenergized since the break contacts 2D2 are open as a result of the previous registration of the down floor call from the second floor. Thus, opening of the make contacts M7 (Fig. 1) as a result of deenergization of the running relay M has no immediate effect on operation, since the parallel break contacts 78-3 remain closed.

After a time sufficient to permit dropout of the non-interference relay 70T (Fig. 1) and after the doors associated with the elevator car A are closed, the following circuit is established:

L1, 70T1, 78-1, X1, F2, 22, D, M, DR1, L2

The energized down switch D closes its make contacts D1 to energize the brake coil for the purpose of releasing the brake. Contacts D2 and D3 close to energize the field winding 15F with proper polarity for down travel of the elevator car. Contacts D4 close to energize the speed relay V. This relay closes its make contacts V1 to shunt the resistor R1. The elevator car now accelerates in the down direction.

Closure of the make contacts D5 establishes a holding circuit around the contacts 70T1, 78-1 and X1. Opening of the break contacts D6 has no immediate effect on the operation of the system.

5 The car running relay M operates in the manner previously described.

As the elevator car proceeds downwardly, the brush ff engages the contact segment f2 (Fig. 2) to complete the following energizing circuit:

L1, 2D1, 2DR2, f2, ff, X4, DST, L2

The energized down stop relay closes its make contacts DST1 (Fig. 1) to complete the energizing circuit for the energizing circuits G, E and F. The relay G closes its holding contacts G1 to establish a holding circuit around the contacts DST1.

When the inductor slowdown relay E comes into horizontal alignment with the slowdown inductor plate DEP for the second floor, a magnetic circuit is completed which results in opening of the break contacts E2 to deenergize the speed relay V. This relay opens its make contacts V1 to introduce the resistor R1 in series with the generator field winding 15F and the elevator car A slows to a landing speed. When the stopping relay F reaches the stopping inductor plate DFP for the second floor, a magnetic circuit is completed which results in opening of the break contacts F2 to deenergize the down switch D and the running relay M.

When deenergized, the down switch D opens its make contacts D1 to deenergize the brake coil 17B. Consequently, the brake shoe 17S is applied against the brake drum 17. In addition, the make contacts D2 and D3 open to deenergize the generator field winding 15F, and the elevator car stops accurately at the second floor. As the car stops, the inductor relays may pass beyond the range in which their cooperating magnetic plates complete the magnetic circuits therefor. Opening of the make contacts D4 and D5 has no immediate effect on the operation of the system. The running relay M, when deenergized, operates substantially in the manner previously discussed with the exception of the effect of the opening of the make contacts M7, as hereinafter explained.

During the stopping of the elevator car A at the second floor, the brush gg (Fig. 2) engaged the contact segment g2. Inasmuch as the break contacts M4 then were closed, the following canceling circuit was completed:

L1, 2D1, 2DN, g2, gg, M4, L2

50 As a result of the energization of the canceling coil 2DN, the registering relay 2D is reset and opens its holding contacts 2D1. Closure of the break contacts 2D2 (Fig. 3) results in energization of the no-call relay 78 for the elevator car A. Closure of the break contacts 2D3 results in pickup of the no-call relay B78 for the elevator car B.

Opening of the break contacts 78-1 and B78-1 (Fig. 1) prevents energization of the running relays M and BM. Thus, until another call for elevator service is registered, the car A will remain parked at the second floor and the car B will remain parked at that floor for which it last provided service.

60 Opening of the break contacts 78-2 has no immediate effect on operation. Opening of the break contacts 78-3 prepares the down preference relay X for subsequent deenergization. Such deenergization occurs upon dropout of the running relay M and the accompanying opening of its make contacts M7. Note that since both the up and the down preference relays W and X, respectively, now are dropped out, the elevator car A is not conditioned for travel in either the up or the down direction, i.e., as long as there is no call for service which may be answered by the elevator car A, no direction preference is established for the car.

75 Next, it will be assumed that a passenger who entered

the elevator car at the second floor registered a car call for the first floor by operation of the car-call push button 1C (Fig. 3). The resulting pickup of the car-call registering relay 1CR is accompanied by closure of its make contacts 1CR1 to establish a self-holding circuit 5 for the relay. Opening of the break contacts 1CR2 results in dropout of the no-call relay 78.

Closure of the make contacts 78-1 (Fig. 1) partially completes an energizing circuit for the running relay M. Closure of the break contacts 78-2 and 78-3 results in 10 the following sequence of operation: The up preference relay W first picks up, since the down preference relay X has a delay in pickup, as heretofore mentioned. Closure of the make contacts W6 (Fig. 3) results in pickup 15 of the call-above relay 78U, which is accompanied by closure of the make contacts 78U1 (Fig. 1) to pick up the reversing relay J. Closure of the make contacts J3 has no immediate effect on operation for the reason that the make contacts 78U1 still are closed. Opening 20 of the break contacts J2 causes the up preference relay W to drop out. Closure of the break contacts W2 results in the completion of an energizing circuit for the down preference relay X through the closed contacts 78-3. Opening of the make contacts W6 (Fig. 3) drops 25 out the call-above relay 78U. Opening of the break contacts X3 (Fig. 1) drops out the reversing relay J, but closure of the break contacts J2 cannot effect pickup of the up preference relay W, since the break contacts X2 now are open.

Thus, the elevator car A now is conditioned for travel in the down direction. After a lapse of time sufficient to permit entry and discharge of passengers relative to the elevator car A, the car A proceeds to the lower terminal floor by a sequence of operations which will be clear from the preceding discussion.

It will be observed that the elevator system as thus far described has provided down collective service for the floors for which corridor calls were registered.

For the next example, it will be assumed that the elevator car A is moving upwardly from the first floor in response to a car call for the fourth floor and that a prospective passenger located on the third floor desires elevator service from such floor in the up direction.

As was mentioned heretofore, a car position indicator is located at each floor for each of the elevator cars of the system. A prospective passenger may be informed thereby of the position and direction of movement of each of the elevator cars. Thus, by observing the position indicator located at the third floor for the elevator car A, the prospective passenger in the present example notes that the car A is moving upwardly toward the third floor. The passenger previously has been instructed that the pressing and holding of a floor call push button will result in the stopping of an up-moving car at his floor. He, therefore, presses and holds the floor-call push button 3F in its actuated position for the few seconds immediately preceding the arrival of the car A at the third floor.

The holding of the push button 3F as the brush ee (Fig. 2) engages the contact segment e3 establishes the 60 following energizing circuit:

L1, 3F, e3, ee, W3, UST, L2

Closure of the make contacts UST1 (Fig. 1) completes an energizing circuit for the relays G, E and F. The energization of these relays causes the elevator car A subsequently to stop at the third floor in a manner which will be apparent from the preceding discussion.

Assume next that the up floor call for the third floor in the preceding example is the only call registered in the system. The engagement of the brush mm (Fig. 3) with the contact segment m3 as the elevator car A approaches the third floor then results in energization of the call-above relay 78U before the call is canceled to pick up the no-call relay 78 to open the latter's break 70 contacts 78-2 (Fig. 1). When energized, the relay 78U closes its make contacts 78U1. Energization of the reversing relay J is prevented, however, since the pickup of the up stop relay UST also resulted in opening of its make contacts UST2. Thus, the break contacts J2 remain closed. When the up floor call for the third floor is cancelled and the no-call relay 78 picks up as a result thereof, its break contacts 78-3 open to drop out the up preference relay W, which results in closure of the break contacts W2. However, since both of the contacts M7 and 78-3 open as the car stops at the third floor, the down preference relay X cannot be energized through the closed contacts W2.

It will be recalled that the up stop relay UST has a time delay in dropout. This delay is sufficient to enable the prospective passenger at the third floor, after he releases the push button 3F and the elevator car A stops at the third floor, to enter the car and register a car call for a floor above before the relay UST times out to close its break contacts UST2. Assume, for example, that the passenger presses the push button 5C (Fig. 3) to register a car call for the fifth floor. As a result thereof, the no-call relay 78 drops out to close its break contacts 78-2 and 78-3 (Fig. 1); but the call above relay 78U is dropped out, and its make contacts 78U1 are therefore open, thus preventing energization therethrough of the reversing relay J when the up stop relay UST times out to close its contacts UST2. (It will be recalled that the brush mm leaves each of its associated contact segments during up car travel in advance of the arrival of the elevator car at the associated floor.) The up preference relay W, therefore, picks up through the contacts J2 and 78-3, and the elevator car A thereby again becomes conditioned for up travel. (It also will be recalled that the down preference relay X has a slight time delay in pickup, enabling the up preference relay W to pick up first; opening of the contacts W2 prevents energization therethrough of the down preference relay X.)

After a time sufficient to permit dropout of the non-interference relay 70T and after the doors associated with the elevator car A are closed, the car A proceeds to the fifth floor, in response to the car call registered by the passenger, by a sequence of operations which will be clear from the foregoing discussion. If no call which may be answered by the elevator car A remains in the system, it will be understood from the preceding discussion that cancellation of the car call for the fifth floor results in the parking of the elevator car A at the fifth floor and the establishment of no direction preference for the car.

Referring to Fig. 2, it will be observed that when a passenger who desires up service from one of the intermediate floors of the building presses and holds one 55 of the push buttons 2F through 5F, one of the break contacts 2DR2 through 5DR2 associated with that push button is maintained in open condition as long as the push button is held. For example, if the push button 2F is pressed and held, the floor call relay 2DR picks up to open its break contacts 2DR2. Opening of the break contacts 2DR2 prevents a down moving elevator car from answering the call for up service from the second floor. Thus, if it is assumed that the elevator car B is traveling in the down direction while the switch contacts of the push button 2F are closed, the open contacts 2DR2 prevent energization therethrough of the down stop relay BDST for the elevator car B when the brush Bff engages the contact segment Bf2 as the car B approaches the second floor.

In the event that both a prospective up passenger and a prospective down passenger desire elevator service from the same floor, the car position indicators provided for that floor will indicate to such passengers when to press and hold their floor call push button to stop an up-moving

car and when to press and release the button to stop a down-moving car. For example, if both a prospective up passenger and a prospective down passenger desire service from the second floor, and if the elevator car A is approaching the second floor in the up direction, as indicated by the car position indicator PI (Fig. 1), the prospective up passenger at the second floor is informed thereby that he must press and hold the floor-call push button 2F in order to stop the car A for up service. Subsequently, the prospective down passenger at the second floor will press and release the button 2F to register a call for down service, as a result of which the next down-moving car will stop at the second floor.

From the foregoing discussion of operation, it will be seen that elevator system herein described, while basically a down collective system, has been provided with an up collective feature.

Although the invention has been described with reference to certain specific embodiments thereof, numerous modifications falling within the spirit and scope of the invention are possible.

I claim as my invention:

1. An elevator system comprising a structure having a plurality of landings, an elevator car, means mounting the elevator car for movement in two directions relative to the structure to serve the landings, and motive means for moving the elevator car relative to the structure, in combination with control means operable in cooperation with the motive means to move the elevator car relative to the structure and to stop the elevator car at predetermined landings, said control means including call registering means for registering calls for elevator service from the landings, said call registering means comprising only a single movable member disposed at each of said landings, first control means responsive to a first mode of operation of each of said members in a first position for registering calls for elevator service in a first direction from the landings, and second control means responsive to a second mode of operation of each of said members in said first position for registering calls for elevator service in a second direction from the landings.

2. An elevator system comprising a structure having a plurality of landings, an elevator car, means mounting the elevator car for movement in two directions relative to the structure to serve the landings, motive means for moving the elevator car relative to the structure, in combination with control means operable in cooperation with the motive means to move the elevator car relative to the structure and to stop the elevator car at predetermined landings, and call registering means for registering calls for elevator service from the landings, said call registering means comprising only a single movable member disposed at each of said landings, said call registering means including means responsive to movement of each of said members to a first position for registering calls for elevator service in a first of said two directions from each of the landings for which said member is moved to said first position, and modifying means responsive to the maintenance of each of said members in said first position as the elevator car approaches each of the landings for which a member is maintained in said first position while traveling in the second of said two directions for registering calls for elevator service in said second direction from the last-named landing.

3. An elevator system comprising a structure having a plurality of landings, an elevator car, means mounting the elevator car for movement in two directions relative to the structure to serve the landings, motive means for moving the elevator car relative to the structure, in combination with control means operable in cooperation with the motive means to move the elevator car relative to the structure and to stop the elevator car at predetermined landings, and means comprising only a single movable member disposed at each of said landings operable for

registering calls for elevator service from the landings, said control means comprising first control means responsive to the movement of each of said members to a first position for moving and stopping the elevator car to provide a first predetermined service for each of the landings for which said member is moved to said first position, and modifying means responsive to the maintenance of each of said members in said first position as the elevator car approaches each of the landings for which a member is maintained in said first position while traveling in a first of said two directions for modifying the moving and stopping of the elevator car to provide a second predetermined service for each of the landings for which said member is operated in the last-named manner.

4. An elevator system comprising a structure having a plurality of landings, an elevator car, means mounting the elevator car for movement in two directions relative to the structure to serve the landings, motive means for moving the elevator car relative to the structure, in combination with control means operable in cooperation with the motive means to move the elevator car relative to the structure and to stop the elevator car at predetermined landings, and means comprising only a single movable member disposed at each of said landings operable for registering calls for elevator service from the landings, said control means comprising first control means responsive to the movement of each of said members to a first position for moving said elevator car to provide elevator service from each of the landings for which said member is moved to said first position, second control means responsive to the movement of each of said members to said first position for stopping the elevator car to provide elevator service in a first of said two directions from each of the landings for which said member is moved to said first position, and third control means for stopping the elevator car to provide elevator service in the second of said two directions from each of the landings for which said member is maintained in said first position as the elevator car approaches the last-named landing in said second direction but not in the first of said two directions.

5. An elevator system comprising a structure having a plurality of landings, an elevator car, means mounting the elevator car for movement in two directions relative to the structure to serve the landings, motive means for moving the elevator car relative to the structure, in combination with control means operable in cooperation with the motive means to move the elevator car relative to the structure and to stop the elevator car at predetermined landings, car-call means operable from the elevator car for registering a call for each of the landings desired for the load within the elevator car, landing call means comprising only a single movable member disposed at each of the landings operable for registering calls for elevator service from the landings, said control means comprising means responsive to the movement of each of said members to a first position for moving the elevator car and for stopping the elevator car to provide service in a first of said two directions from each of the landings for which said member is moved to said first position, reversing means for causing the elevator car while traveling in the second of said two directions to stop and to condition the elevator car for subsequent travel in the first direction at the farthest landing in the second direction for which a landing call is registered provided no car call is registered requiring further travel of the elevator car in the second direction, and modifying means responsive to the presence of each of said members in said first position as the elevator car approaches in the second direction a landing for which said member is so operated for stopping the elevator car at the last-named landing, for rendering said reversing means ineffective for a predetermined time to condition the elevator car for sub-

sequent travel in the first direction although no landing call and no car call previously has been registered requiring further travel of the elevator car in the second direction and for permitting the registration of a car call in response to operation of said car-call means during such predetermined time for a landing requiring further travel of the elevator car in the second direction.

6. An elevator system comprising a structure having a plurality of landings including first and second terminal landings and a plurality of landings intermediate the terminal landings, an elevator car, means mounting the elevator car for movement in two directions relative to the structure to serve the landings, motive means for moving the elevator car relative to the structure, in combination with control means operable in cooperation with the motive means to move the elevator car relative to the structure and to stop the elevator car at predetermined landings, and bypassing means operable from each of said intermediate landings for preventing said elevator car from stopping at a landing for which said bypassing means is operated.

7. In an elevator system for a structure having a plurality of landings including first and second terminal landings and a plurality of landings intermediate the terminal landings, a plurality of elevator cars, means mounting the elevator cars for movement in two directions relative to the structure to serve said landings, motive means for moving each of the elevator cars relative to the structure, and control means operable in cooperation with the motive means to move the elevator cars relative to the structure and to stop the elevator cars at predetermined landings, and means comprising only a single movable member disposed at each of said landings for registering calls for elevator service from the landings, said control means comprising first control means responsive to the movement of each of said members to a first position for moving said elevator cars and for stopping said elevator cars to provide service in a first of said two directions from each of the landings for which said member is moved to said first position, and modifying means responsive to the maintenance of each of said members in said first position as an elevator car approaches in the second of said two directions a landing for which said member is so operated for stopping the last-named elevator car at the last-named landing and for preventing any elevator car which approaches the last-named landing in said first direction from stopping at such landing.

8. In an elevator system for a structure having a plurality of landings including first and second terminal

landings and a plurality of landings intermediate the terminal landings, a plurality of elevator cars, means mounting the elevator cars for movement in two directions relative to the structure to service said landings, motive means for moving each of the elevator cars relative to the structure, control means operable in cooperation with the motive means to move the elevator cars relative to the structure and to stop the elevator cars at predetermined landings, car-call means operable from each of the elevator cars for registering a call for each of the landings desired for the load within the associated elevator car, landing call means comprising only a single movable member disposed at each of the landings operable for registering calls for elevator service from the landings, said control means comprising means responsive to the movement of each of said members to a first position for moving the elevator cars and for stopping the elevator cars to provide service in a first of said two directions from each of the landings for which said member is moved to said first position, reversing means for causing each of the elevator cars while traveling in the second of said two directions to stop and for conditioning such elevator car for subsequent travel in the first direction at the farthest landing in the second direction for which a landing call is registered which may be answered by such elevator car provided no car call is registered requiring further travel of such elevator car in the second direction, and modifying means responsive to the maintenance of each of said members in said first position as an elevator car approaches in the second direction a landing for which said member is so operated for stopping the last-named elevator car at the last-named landing, for rendering said reversing means ineffective for a predetermined time to condition said last-named elevator car for subsequent travel in the first direction although no landing call and no car call previously has been registered requiring further travel of said last-named elevator car in the second direction, for permitting the registration of a car call in response to operation of the car-call means for said last-named elevator car during such predetermined time for a landing requiring further travel of said last-named elevator car in the second direction, and for preventing any elevator car which approaches said last-named landing in said first direction from stopping at said last-named landing provided no car call is registered for such elevator car for said last-named landing.
